JOHN E. PERRY, OF SHARON, PENNSYLVANIA, ASSIGNOR TO VALLEY MOULD AND IRON CORPORATION, OF SHARONVILLE, PENNSYLVANIA, A CORPORATION OF NEW YORK.

CORE BOX FOR INGOT MOLDS OR THE LIKE.

Application filed May 22, 1926. Serial No. 110,834.

The present invention relates broadly to metallurgy and more especially to a core box for use in manufacture of cores for casting ingot molds or the like.

Heretofore in the art, it has been customary to surround a core bar with a wooden box and then ram sand in the space between the core bar and the box in order to form a sand facing on the core bar. The wooden structure tended to yield under the ramming operation and the result was lack of uniformity in the finished sanded core bars. It has also been proposed to utilize metal boxes to surround the core bar and comprise faces against which sand was rammed in order to form the sand facing on the bar. The metal boxes while of sufficient strength to sustain the ramming operations to accurately form the sand face, resulted in high equipment charges because the faces of the core boxes required machining and where a customer for ingot molds desired to change the corner radius on their molds or to change the matrix of the mold it was necessary to cast and machine entire new sections forming the sides of the core box.

The present invention overcomes the difficulties of the known prior art by providing a core bar box having strong supporting sides with the inside walls thereof preferably vertical. These inside walls are adapted to support liners which are formed with inside faces of such contour that when the sides of the box are matched up the matrix of the core box is exactly that which will be the matrix of the ingot mold cast from a core bar that is rammed in this lined core box. Where a different shape or different taper or different corner of radius is desired, all that is necessary is to change the lining to secure the desired shape. By this construction, full advantages in strength, rigidity, and accuracy of a full metal core box is attained together with the greatest possibility of flexibility in shapes and designs, by merely carrying a stock of liners to be fitted in the core box to form the shapes desired. While the liners for economy and ease of working preferably are formed of wood, it is to be understood that metal or any other suitable substance may be used in making the liners,

the principal attribute of the present invention being a supporting frame or shell to provide strength and rigidity to support interchangeable side members comprising the 55 facings against which the core bar sand is rammed when the core bar is being sand faced.

Other and further attributes and objects of the present invention will in part be obvious and will in part be pointed out herein-after in the specification, and distinctly specified in the claims.

It is realized, however, that the present invention may be embodied in structures 65 other than those herewith specifically disclosed and therefore it is to be understood that the disclosure is to be as illustrative and not in a limiting sense.

Fig. 1 is a view illustrating a vertical section taken substantially on line A—B of Fig. 2.

Fig. 2 is a plan view showing a section taken on line C—D of Fig. 1.

Fig. 3 is a detailed view of a portion of 75 one side of a liner of a shape different from that illustrated in Fig. 2.

The preferred embodiment of the present invention comprises a core box base 1 preferably provided with raised guides 2 and 80 with an open socket 4 adapted to receive the base of a suitable core bar. The supporting sides of the core box comprise four members 85 preferably made of cast iron and having side walls 5 provided with strengthening ribs 6 and 7 and corner ribs 8. The corner ribs of adjacent sides are adapted to be bolted together as at 9 and 10 to secure pairs of the sections together to form sides of the core box; with one side connected to the hinge 80 member 11, and the other side connected to the other hinge member 12, with both hinge members being adapted to rotate around the pivot 14 carried by the base 1. When the box is closed, the supporting sides are adapted to be clamped together by a C-clamp 15. Preferably, the side walls 5 are substantially vertical and without tapering.

The side walls 5 may be provided with openings through which bolts 16 may extend 100 to securely clamp sections 17 of the inside liner to the side face of the supporting side

walls. The inside liner may be formed of any desired material, but preferably is constructed of wood, which is easily worked and the inside surface of the liner sections is shaped to provide the proper contour to the sanded surface of the core bar. In other words, the matrix of the inside of the liners, when the core box is closed, will be the same as the matrix of the ingot mold which is to be cast around the core bar that will be sand faced in the core box.

From the foregoing, it follows that the inside face of the liner 17 may be tapered and it may have corners of a predetermined radius, and side faces of the contour desired. When a different mold matrix is desired, the liner is removed and a different liner is set in place in the core box thereby providing the change in matrix of the core box without necessitating a change in the heavy and expensive parts of the equipment. Where bolts are used to retain the liner sections in position, as is illustrated in the drawings, the bolt heads may be covered by suitable fillers 18 which may be smoothed to the same surface as the inside face of the liner so that the inside surface of the core box, with the liner in position, is a smooth finished surface.

The drawings illustrate the core box as comprising four sides of substantially the same construction and the liner 17 is likewise illustrated as being formed of four side pieces adapted to join together at the corners. It is to be understood that the number of sections to either the core box side walls or the liner sections is immaterial, in that joints may be formed wherever it is most convenient or best suited to the particular constructions in use.

Having described my invention, I claim:

1. In a core box for use in sanding core bars to be used in manufacture of ingot molds, the combination of supporting means, and liners supported by said supporting means, said liners having work faces adapted to form matrix side walls which predeter-

mine the side wall faces on the sanded core bar.

2. In a core box for use in sanding core bars for ingot molds, the combination of supporting side walls, and detachable liners supported by said side walls, said liners having work faces to predetermine the faces to be formed on the sanded core bar. 55

3. In a core box for use in making core bars for ingot molds, the combination of substantially flat supporting side walls, interchangeable liners adapted to be carried by and supported by said flat side walls, and means to detachably secure said liners to said side walls, said liners having work faces adapted to predetermine the surfaces on a core bar sand rammed in said core box. 60

4. A core box for use in making sand cores for ingot molds comprising movable side walls, interchangeable wooden liners carried by said side walls, and means for detachably securing such liners to said side walls. 65

5. A core box for use in manufacturing sand cores for ingot molds comprising cast iron sections secured together to form box like sides for said core box, a base member to which said sides are hinged and wooden liners supported by said box-like sides and adapted to be interchanged with other liners without changing said box-like sides. 70

6. An article of manufacture, a core box for making sand cores for ingot molds, said core box comprising movable cast iron sides, wooden liners adapted to fit within said cast iron sides and provided with work faces to form the matrix of the core box, and means to detachably secure said liners to said side walls. 75

7. A core box for making sand cores for ingot molds, said core box comprising a base member, a pair of hinged cast iron sides supported by said base member, and interchangeable wooden liners mounted within and supported throughout their length by said hinged sides. 80

JOHN E. PERRY.
